UNITED STATES PATENT OFFICE

153,313

DESIGN FOR A COMBINED CEILING-MOUNTED VENTILATING AND ILLUMINATING APPARATUS

Leonard R. Phillips, Teaneck, N. J., assignor to
Anemostat Corporation of America, New York,
N. Y., a corporation of Delaware

Application May 1, 1947, Serial No. 138,744

Term of patent 7 years

(Cl. D48—23)

To all whom it may concern:

Be it known that I, Leonard R. Phillips, a citizen of the United States, residing at Teaneck, in the county of Bergen and State of New Jersey, have invented a new, original, and ornamental Design for a Combined Ceiling-Mounted Ventilating and Illuminating Apparatus, of which the following is a specification, reference being had to the accompanying drawing, forming a part thereof.

Fig. 1 is a perspective view of a combined ceiling-mounted ventilating and illuminating apparatus, showing my new design.

Fig. 2 is a side elevation thereof.

The design forming the subject matter of the present invention is for a combined ceiling-mounted ventilating and illuminating apparatus of arbitrary over-all length and width.

The characteristic features of my design reside in those portions shown in full lines.

I claim:

The ornamental design for a combined ceiling-mounted ventilating and illuminating apparatus, substantially as shown and described.

LEONARD R. PHILLIPS.
